UNITED STATES PATENT OFFICE.

EMORY C. HISCOCK, OF CHICAGO, ILLINOIS, ASSIGNOR TO W. W. KIMBALL COMPANY, OF CHICAGO, ILLINOIS, A CORPORATION OF ILLINOIS.

PNEUMATIC PLAYER-ACTION.

1,089,765.

Specification of Letters Patent.

Patented Mar. 10, 1914.

Original application filed March 2, 1910, Serial No. 546,809. Divided and this application filed September 17, 1910. Serial No. 532,451.

To all whom it may concern:

Be it known that I, Emory C. Hiscock, a citizen of the United States, residing in Chicago, in the county of Cook and State of Illinois, have invented certain new and useful Improvements in Pneumatic Player-Actions, of which the following is a specification.

This invention relates to pneumatic actions for mechanical piano players, and has reference more particularly to improvements in that class or type of such pneumatic actions as employ a main exhaust chamber or chest which is in free communication with one side of a diaphragm that actuates a valve controlling the alternate communication of the atmosphere and the exhaust with the interior of the action bellows, and is also in valve-controlled communication with the opposite side of the said diaphragm and with the tracker-range. As is well known, in mechanisms of this character there is commonly employed a vent regulating or "bleed" valve that regulates the effect of the exhaust in the main exhaust chamber or chest upon the tracker-range and one side of the said diaphragm. These vent regulating valves, of which there is one for each pneumatic, are commonly of the needle valve variety having a screw-threaded mounting whereby they are capable of fine adjustment to secure exactly the required venting effect upon the air in the tracker and diaphragm ducts. The proper adjustment of these numerous valves is a matter of considerable nicety, requiring a high degree of skill and involving considerable labor and experiment; and as these valves have hitherto been commonly located in position more or less difficult of access, the proper regulation of the action in this respect has proved a source of considerable difficulty and expense to manufacturers of these instruments.

The main object of the present invention has been to provide such a structure and organization of the parts, including the vent regulating valves, as would render the latter most easy of access for purposes of adjustment and most efficient in operation; and with this object in view, the invention comprises as its main feature the location of such vent regulating valve in the unobstructed front wall of the main exhaust chamber having a duct communicating with

said exhaust chamber and with the tracker range and diaphragm which controls the valve of the action bellows, said valve controlling the communication of said duct with the main exhaust chamber.

In the accompanying drawing I have illustrated one practical form in which the invention may be embodied, the figure showing a vertical section through the primary exhaust chest, underlying diaphragm chamber, and the tracker range of a well-known form of player piano.

Referring to the drawing, 10 designates the main exhaust chamber or chest, above which pipes 11 lead to the usual tracker range 12 of the instrument. Each pipe 11 connects with a vertical duct 13 formed through the back wall of the exhaust chest 10, said duct 13 communicating with a horizontal duct 14 in the forwardly extending bottom wall of the exhaust chamber 10, and the duct 14 communicating with a vertical duct 15, the lower end of which communicates by a short inwardly extending duct 16 with the lower side of a diaphragm 17 mounted in the bottom of a diaphragm chamber 18, which latter is in communication with and subject to the same degree of vacuum as that existing in the exhaust chamber 10. Mounted on the diaphragm 17 is a T-shaped valve 19 which extends upwardly into a valve chamber 20 above the diaphragm chamber 18 and co-operates alternately with lower and upper valve seats 21 and 22 at the lower and upper ends of said valve chamber 20, respectively. The stem of the valve 19 is hollow and is guided on a vertical pin 23 depending from the upper annular valve seat 22. From the valve chamber 20 a duct 24 leads directly into the action bellows 25; while, when the valve 19 is withdrawn from its upper seat 22, the upper end of the valve chamber 20 is in free communication with the atmosphere through said hollow valve seat and a horizontal duct 26 lying between the ducts 14 and 24.

The front wall of the exhaust chest 10 has a series of vertical ducts 27 that communicate at their lower ends with the ducts 14. Mounted in the front wall of the exhaust chest 10 and intersecting each of the vertical ducts 27 is a hollow valve-holder or casing 28 of a generally cylindrical form having a head 29, a threaded bore, and a substantially

central circumferential groove 30 lying in the vertical plane of the duct 27, with one or more radial holes 31 forming a communication between the groove 30 and the interior of the valve-holder. This latter is also formed with a contracted portion forming an internal valve seat 32 at its inner end adapted to be controlled as a vent opening between the exhaust chest 10 and the duct 27 by a needle valve 33 that is formed with a screw-threaded stem or shank 34 having threaded engagement with the bore of the holder or valve-casing 28. This valve holder is preferably made of hard rubber or what is known as hard rubber composition, since I have determined by experiments that this material is free from contraction and expansion at ordinary room temperatures to any such extent as to displace the valve from correct adjustment; and it also grips the stem or shank of the valve under a high degree of friction, and thus prevents accidental turning of the valve therein. The novel details of the valve, *per se*, however, form no part of the present invention, but are made the subject matter of an application filed by me on the 2nd day of March 1910, Serial No. 546,809, of which the present application forms a division.

In player pianos, the mechanism of the pneumatic action herein shown is usually mounted in such a way that the removal of the upper front panel of the piano-case exposes the front wall of the main exhaust chest or chamber 10. By extending the

vent-duct into such front wall and locating the vent regulating valve therein, easy access is afforded to the latter for adjustment without requiring removal of the pneumatic action or any further dismantling of the piano-case. Since the adjustment of these valves has to be made after the pneumatic action has been assembled and positioned within the piano-case, it will be manifest that the described construction and location of the vent-regulating valves effect a decided economy in the time and labor required to effect their proper adjustment.

I claim:

In a pneumatic player action of the character described, the combination with the action-bellows, the action-bellows valve, the diaphragm controlling said valve, and the tracker-range, of a main exhaust chamber having an unobstructed front wall and a duct formed in said front wall and communicating through its lower end with one side of said diaphragm and with the tracker range, of a vent valve casing mounted in said front wall of said exhaust chamber and communicating interiorly with said exhaust chamber and said duct, and a needle-valve adjustably mounted in said valve-casing and controlling communication between the interior of the latter and said exhaust chamber, substantially as described.

EMORY C. HISCOCK.
